UNITED STATES PATENT OFFICE.

WILLIAM M. DUCKER, OF NEW YORK, N. Y.

CORSET-FASTENING.

SPECIFICATION forming part of Letters Patent No. 398,036, dated February 19, 1889.

Application filed November 16, 1888. Serial No. 290,992. (No model.)

To all whom it may concern:

Be it known that I, WILLIAM M. DUCKER, a citizen of the United States, residing in the city of New York, in the county and State of New York, have invented certain new and useful Improvements in Corset-Fastenings; and I do hereby declare the following to be a full, clear, and exact description of the invention, such as will enable others skilled in the art to which it appertains to make and use the same, reference being had to the accompanying drawings, which form part of this specification.

My invention relates to corset-fastening devices which will hold the parts securely in position against the ordinary pressure or strain to which a corset is usually subjected, so that it cannot become unfastened by any of the ordinary movements of the body of the wearer, by the use of which the corset can be quickly fastened and unfastened, which are simple and can be cheaply made and readily applied to corset-steels of the kind commonly in use, which will project but little beyond the steels, and which can be readily covered to present a neat appearance by the usual coverings employed for such purpose.

In the drawings, Figure 1 is a front view of corset-steels uncovered, showing my fastenings applied and engaged to hold the parts together. Fig. 2 is a similar view with the fastenings disengaged. Fig. 3 is an enlarged plan view of the catch *b*. Fig. 4 is a section on the line *x*-*x* of Fig. 3 and a side view of the catch *e*. Fig. 5 is a plan view of the catch *c*, also enlarged. Fig. 6 is a front view of part of a corset, showing my improvement applied and the steels covered. Fig. 7 is an edge view of the side *G* of the corset, showing the openings for receiving the engaging ends of the catches *e*.

Similar letters of reference indicate like parts in all the drawings.

A and *B* are corset-steels of any ordinary kind in use. On the steel *A* receiving-catches *a*, *b*, and *c* are secured, and on the steel *B* engaging-catches *d* *e* are secured in any well-known manner, as by suitable rivets.

The receiving-catch *a* consists of a flat piece of metal provided with an opening, *a'*, which is directly riveted to the steel *A*, and in order to permit the opening to be abun-

dantly large for the reception of the hook part *d* without having the part *a* project unnecessarily beyond the steel *A*, that steel may be recessed slightly at the opening *a'*, as indicated in Fig. 2. The engaging-catch *d* is provided at its end with a hook, *d'*, formed by turning its end back upon itself, and this hook *d'* is of suitable length to make secure engagement in the hole *a'* with the part *a*. The engaging-catches *e* are all alike and are made by bending up at a right angle the ends *e'* of the catch-piece *e*, as shown clearly in Fig. 4.

The receiving-catch *c* consists of two parts. The upper slotted part, *c*, has a suitable slot, *c'*, to take in the bent-up end *e'*, this part being made of spring metal. Under this and between it and the steel *A* a guide-plate, *g*, is secured, which consists of a thin piece of metal conveniently secured in place by the rivets that fasten the piece *c* to the steel *A*. This guide-plate *g* is provided with a bent-over end, *f*, between which end and the steel *A* the edge of the covering corset-cloth is inserted, and this end *f* prevents the edge of the corset-cloth working into the channel or guideway provided for the entrance of the engaging end of the catch *e*. The edges *g'* *g'* of the part *g* are bent up on each side, and upon these bent-up parts rests the spring-catch *c*. Thus a channel or guideway is formed between them for the ready insertion of the end *e'* of the catch *e*.

The receiving-catch *b* is similar to the catch *c*; but instead of having a slot, *c'*, inclosed on four sides it is provided with a slot, *c²*, open at the bottom, the upper spring-piece being cut away rounding, as clearly shown at *i* in the drawings. In this catch the lower upturned part of the guide-piece *g* is made flaring downward, as indicated at *g²*, and allows the part *e'* of the hook *e* engaging therewith to be disengaged on being pulled downward and outward, passing between the raised part *g²* and the rounded edge *i* of the spring-piece *b*. In sewing the corset-coverings onto the steels the seam must be so adjusted that no part of the cloth will come into the way of the ends *e'* of the engaging-hooks *e*, the seams terminating on each side of the receiving-catches, as clearly shown in Fig. 7.

By this arrangement of the catches very im-

portant advantages are secured. In the first place, the cloth covering can be readily secured over the steels in a proper manner, as the outer edges of the parts *a c* and the upper edge of the part *b* and flaring shoulder *g*² of the central catches form distinct guides for the sewers. The engaging surfaces do not chafe upon the cloth of the covering as the engaging pieces *e*, which are required to pass under the covering cloth, pass into a metal guideway consisting of the under side of the upper spring-catches, the guide-plate *g*, and side shoulders, *g' g'* or *g' g*². By this arrangement of the parts the corset-steels can also be neatly covered, leaving only small portions of the fastenings projecting.

The operation of my invention is as follows: The hook *d'* is first caught into the eye *a'*. When that is done, it is only necessary to bring the lower parts of the steels together, as the engaging parts *e' e'* readily pass into the channels provided for them and snap into their respective slots. In disengaging the corset the upper and lower catches are first disengaged, the lower catch by slightly turning the outer edges of the steels *A B* toward each other outwardly, which will force up the outer edge of the spring-plate *c* and disengage the catch *e'* from the slot *c'*, and the upper catch by twisting the hook *d'* out of the eye *a*, and when these two catches are disengaged a slight downward pull of the steel *B* will bring the catch parts *e' e'* of the intermediate fastenings, *b b*, opposite the rounded portions *i* of their spring-catches *b b*, when the pressure of the body of the wearer within the corset will separate the parts, the portions *e' e'* disengaging from their respective catches by moving outward between the flaring shoulders *g*² and the rounded portions *i*.

I have shown two of the open-slotted catches disposed between the locking or end catches, and this number I have found most convenient for general use, as this form of catch is

used to advantage on that part of the steel 45 where the greatest pressure is exerted by the body of the wearer when the corset is in use; but I do not limit myself to any particular number of such open-slot catches in any cor- 50 set.

I do not claim in this application the closed slot-catch *c*, as that is the subject of an independent application for a patent now pending filed September 25, 1888, Serial No. 286,318; but,

Having thus described my invention, what I claim as new, and desire to secure by Letters Patent, is—

1. The combination of the corset-steels *A B*, provided with the eye *a* and hook *d* catch, at one 60 extremity, and the closed slot *c* and engaging-piece *e* catch, at the other extremity, and having between such catches one or more catches consisting of an engaging part, *e*, and spring-piece *b*, having an open slot, *c'*, a rounded cut-away part, *i*, a guide-plate, *g*, with turned-under part *f*, shoulder *g'*, and downwardly-flaring shoulder *g*², adapted to permit the engaging part *e* to be withdrawn by a downward and outward movement, substantially as described 65 and shown.

2. The corset-fastening described, consisting of the spring catch-piece *b*, provided with the open slot *c'*, and having a rounded edge, *i*, a supporting guide-piece, *g*, provided with a 70 turned-under portion, *f*, the upturned supporting part *g'*, and upturned supporting part *g*², flaring away from the rounded edge *i*, in combination with the engaging part *e* and catch *e'*, adapted to enter between the guide-piece *g* and spring-piece *b*, to engage in the slot *c'*, and to be disengaged by being drawn downward and outward, substantially as described and shown.

WILLIAM M. DUCKER.
